DESIGN FOR A CONCERT PIANO

Charles Loitsch, New York, N. Y.

Application June 22, 1927, Serial No. 69,980

Term of patent 7 years

To all whom it may concern:

Be it known that I, Charles Loitsch, a citizen of the United States and resident of New York city, in the county of New York, and State of New York, have invented a new, original, and ornamental Design for a Concert Piano, of which the following is a specification, reference being had to the accompanying drawing, forming a part thereof.

Fig. 1 is a perspective view of a concert piano, showing my new design.

Fig. 2 is a side elevational view looking in the direction of the arrows 2—2 of Fig. 1.

Fig. 3 is a perspective view of same, with the piano cover open.

Fig. 4 is a top plan view of Fig. 3, looking in the direction of the arrows 4—4 of Fig. 3.

I claim:

The ornamental design for a concert piano, as shown,

CHARLES LOITSCH.
